UNITED STATES PATENT OFFICE

141,672

DESIGN FOR A HOME LAUNDRY WASHING MACHINE

Jack Barofsky, Los Angeles, Calif.

Application March 26, 1945, Serial No. 118,700

Term of patent 14 years

(Cl. D49—1)

To all whom it may concern:

Be it known that I, Jack Barofsky, a citizen of the United States, residing at Los Angeles, in the county of Los Angeles and State of California, have invented a new, original, and ornamental Design for a Home Laundry Washing Machine, of which the following is a specification, reference being had to the accompanying drawings, forming part thereof.

The side opposite that shown in the drawings is the same as the side illustrated.

The dominant features of my design are shown in solid lines in the drawings.

I claim:

The ornamental design for a home laundry washing machine, as shown and described.

JACK BAROFSKY.
